US00D994668S

(12) **United States Design Patent** (10) **Patent No.:** **US D994,668 S**
(45) **Date of Patent:** **** Aug. 8, 2023**

(54) **DATA CAPTURE DEVICE**

(71) Applicant: **ZEBRA TECHNOLOGIES CORPORATION**, Lincolnshire, IL (US)

(72) Inventors: **Huang Chih Huang**, Taoyuan (TW); **Steven D. Sieckowski**, Port Jefferson, NY (US); **Roland Wing Fai Lee**, Jericho, NY (US)

(73) Assignee: **Zebra Technologies Corporation**, Lincolnshire, IL (US)

(**) Term: **15 Years**

(21) Appl. No.: **29/781,760**

(22) Filed: **Apr. 30, 2021**

(51) LOC (14) Cl. **14-02**

(52) U.S. Cl.

CLAIM

We claim the ornamental design for a data capture device, as shown and described.

DESCRIPTION

FIG. 1 is a first perspective view of a data capture device; FIG. 2 is a second perspective view thereof; FIG. 3 is a right side view thereof; FIG. 4 is a left side view thereof; FIG. 5 is a front side view thereof; FIG. 6 is a rear side view thereof; FIG. 7 is a top side view thereof; and, FIG. 8 is a bottom side view thereof.

Broken lines seen in the drawings depict portions of the data capture device that form no part of the claimed design.

1 Claim, 8 Drawing Sheets
